UNITED STATES PATENT OFFICE.

ARTHUR W. WELLINGTON, OF WATERBURY, CONNECTICUT, ASSIGNOR TO WATERBURY M'F'G CO., OF WATERBURY, CONNECTICUT, A CORPORATION.

DESIGN FOR A PORTABLE ELECTRIC-LAMP BASE.

51,848.

Specification for Design.

Patented Mar. 5, 1918.

Application filed December 29, 1917. Serial No. 209,584. Term of patent 14 years.

To all whom it may concern:

Be it known that I, ARTHUR W. WELLINGTON, a citizen of the United States, residing at Waterbury, in the county of New Haven and State of Connecticut, have invented a new, original, and ornamental Design for a Portable Electric-Lamp Base, of which the following is a specification, reference being had to the accompanying drawing, forming part thereof.

The figure is a side view of a portable electric lamp base, showing my new design.

I claim:

The ornamental design for a portable electric lamp base, as shown.

ARTHUR W. WELLINGTON.

Witnesses:

A. C. RECKER,
J. S. NEAGLE.
